UNITED STATES PATENT OFFICE.

HARRY E. ASBURY, OF PHILADELPHIA, PENNSYLVANIA.

HAND-GRENADE AND OTHER EXPLOSIVE SHELL.

1,234,943.

Specification of Letters Patent. Patented July 31, 1917.

Application filed February 18, 1916. Serial No. 79,139.

To all whom it may concern:

Be it known that I, HARRY E. ASBURY, a citizen of the United States, residing in Philadelphia, Pennsylvania, have invented 5 certain Improvements in Hand-Grenades and other Explosive Shells, of which the following is a specification.

My invention relates to munitions of war and more particularly to explosive devices 10 of the self-contained type. It consists of certain improvements in the mechanism for controlling the firing pin or bolt, or a member performing the same function particularly applicable for use with that form of 15 explosive device known as a "hand grenade"; the same comprising a hollow metal shell suitably formed and which may contain some form of high explosive material, such explosive material being set off by detonating means normally held out of action 20 when the structure is not in use, but automatically brought into action by the release of means retaining a firing pin or bolt, which release is effected just prior to the 25 hurling by hand or other projection of the structure. While particularly applicable to structures of the hand grenade type, the mechanism constituting my invention, or simple modifications of the same within the 30 scope of my invention, may be applied to other forms of explosive missiles; shrapnel and the like.

My invention relates more particularly to the means for holding the actuating mechanism in a quiescent state, or out of action 35 prior to the projection of the structure; such means including an externally operable button or trigger which is retracted to release the retaining means and permit the 40 desired action of the firing pin or bolt, or a member performing the same function. This release takes place after the grenade, shell, or other explosive structure has left the hand or other hurling member.

A further feature of my invention is to 45 provide a hand grenade that is somewhat heavier at the striking point than at its opposite point; in other words, a structure that is overbalanced to an extent sufficient to cause it to fall in one position whereby its striking bolt releasing means may be actuated upon impact in order that explosion 50 may occur at once.

A further feature of my invention is to

support the striking bolt releasing means in 55 the projected, active position by means of a relatively light spring which will be compressed upon impact.

A further feature of my invention is to provide a hollow striking bolt or pin 60 adapted to receive the detonator, and the priming cap for igniting the same; no intervening fuse being employed, and to provide a firing pin for such cap in one wall of the hand grenade; the firing pin or striking bolt 65 being susceptible of movement relatively to each other.

A further feature of my invention is to provide such form of hand grenade with an enlarged head or cap carried by the impact 70 end of the same so that sufficient surface to effect release of the parts will be present should the grenade strike in water.

A further feature of my invention consists in applying certain of the details of construction to shrapnel or other explosive shells of a similar character.

In the preferred construction, the grenade is designed to be hurled by the use of a stick which may be secured to the end of the 80 same, or it may be arranged to be shot from a gun. It will be understood, further, that it may be thrown by hand without the use of the throwing stick.

These and other features of my invention 85 are more fully described hereinafter, reference being had to the accompanying drawings, in which:

Figure 1, is a vertical section of my improved hand grenade, showing the releasing 90 mechanism for supporting the striking member in the set and inactive position;

Fig. 2, is a view similar to Fig. 1, showing the releasing mechanism displaced and the striking member with its primary cap in 95 contact with the firing pin;

Fig. 3, is a sectional view of the end of the grenade structure showing a modification within the scope of the invention;

Fig. 4, is a sectional view showing the application of the striking member releasing means to shells of the shrapnel type;

Fig. 5, is a plan view of the structure shown in Fig. 4, and

Figs. 6 and 7, are views illustrating further modified arrangements of the striking member holding means as applied to shrapnel shells.

In Figs. 1 and 2 of the drawings, 1 represents the shell of a hand grenade made in accordance with my invention, of suitable size and weight, which may be made of cast metal, iron for instance; preferably scored or grooved externally in a plurality of directions so that upon bursting, due to the explosion of any contained material, the shell will separate into a great number of fragments. The annular scores are shown at 2, and it will be understood that the shell will be provided with other scores or grooves substantially at right angles to the scores or grooves 2. The shell is preferably provided with a loading opening 4, normally closed by a screw plug 5.

Within the shell a casing 6 is mounted having a chamber 7 for the reception of a movable striking member 8, which may be hollow and provide a chamber 9 for the reception of a detonating cap 10 and a primary cap 11; the end of said member 8 constituting an anvil for said primary cap whereby the latter may be exploded upon engagement with a firing pin. Motion is transmitted to the member 8 by a coiled spring 12 when said member is released; such spring being normally compressed and held by means hereinafter described.

The rear end of the grenade is closed by a wall 15, preferably made of sheet metal and having an open center, with a sleeve 16 for the reception of a throwing stick 17, while interposed between a shoulder 18 of said rear wall and the casing 6, I provide a pressed metal cup member 19, the center of which is preferably struck up to provide a firing pin 20, for engagement with the primary cap carried by the movable member 8, when the latter is released and projected by the spring 12.

At the opposite end of the shell of the grenade a shoulder 21 is provided, and seated on this shoulder is a cupped member 22 having a short flange 23 fitting within the upper end of the casing 6, and between which and a shoulder 24 on the member 8 the coiled spring 12 is confined. By preference, the flange of the cup member is slightly grooved, and the end of the casing 6 may be spun into engagement therewith. Mounted on top of the cupped member 22 is a disk or plate 25, which is held in position and confined in place by a screw cap or plug 26 substantially closing the end of the grenade shell.

The upper end of the member 8 is provided with a shouldered head 27 and, as indicated in Fig. 1, this head is engaged by supporting members or latches 28 of a peculiar shape, which are disposed in slots 29 formed in the plate 25; each of said latches having a foot 30 adapted to underlie and engage the head of the member 8, and a shoulder 31 which rests upon said disk or plate 25. The

latches 28 are spread apart and held in the operative position to support the member 8 by means hereinafter described.

Centrally disposed with respect to the screw plug 26 is an externally operable releasing member or button 35, which is supported in the outwardly projected position by a relatively light spring 36, and which may be held locked in such position prior to the time of use by means of a cotter pin or similar safety key 37; such member or button 35 having a flange 38 engaging a seat 39 in the screw plug 26, and having a projection 40, whereby the spring may be maintained in proper central position; the plate 25 also having a central projection 41 for said spring. The member 35 carries an inwardly projecting stem 42 with an annular portion 43, which, in the normal or inactive position, lies between the latches 28 in order that their lower ends may be held under the upper flanged end 27 of the member 8 and maintain the latter in the inactive position.

When it is desired to use the grenade, the locking or retaining pin 37 is removed from the member 35; thereby rendering the latter free for retraction upon impact. The grenade is then hurled either by hand, or by the aid of the throwing stick 17, or shot from a gun of suitable type.

The overweighting of the grenade shell as before described causes the end carrying the member 35 to strike first. Such impact moves it rearwardly against the tension of the spring 36; displacing its portion 43 from engagement with the latches, and the latter are released, as illustrated in Fig. 2, from their engagement with the member 8, whereupon the spring 12 forcibly moves said member 8 through the shell, 6, bringing the primary cap into engagement with the central firing pin 20 at the base of said shell. The explosion of the primary cap is communicated directly to the detonating cap 10 within the chamber 9 of the member 8, with the consequent rupture of the entire structure under the influence of the high explosive contained within the hollow space of the grenade shell. To prevent displacement of the detonating cap 10 with respect to the primary firing cap 11, I may fill any space left in the chamber 9 of the member 8 by a packing of cotton or similar material, indicated at 44.

If desired to protect the firing mechanism from gases, fumes or other deteriorating influence emanating from the charge of explosive, which is preferably disposed within the hollow space of the grenade shell and surrounding the casing 6, a washer 45 of suitable material, may be interposed between the end of the casing 6 and its seat on the member 19; another indicated at 46 between a portion of the rear wall 15 of the casing

and said member 19, and another indicated at 47 between the cup 22 and its seat on the shoulder or flange 21 of the shell.

In cases where water is encountered and there is danger of the grenade landing in water instead of striking solid resistance, it may be desirable to provide the member 35 with an enlarged striking face, and for such purpose I may provide a cap 50 as illustrated in Fig. 3. This cap may have a centrally threaded stem 51 adapted to a threaded socket 52 in the end of the member 35, and this member, as shown in Figs. 1 and 2, may be socketed for this purpose. In order that the member 35 carrying this enlarged surface cap 50 may be held against accidental displacement, I preferably provide the cap with suitable protective means, which may be in the form of a split cotter pin 53 with its legs slightly bent to insure maintenance of the member 35 and its cap 50 in the normal outward position, but not preventing its removal at the desired time, which removal may be assisted by the employment of a ring 54.

The holding and releasing mechanism for the member 8 described with reference to use in a hand grenade may, with certain relatively unimportant modifications, be applied to the ends of explosive shells of a wide variety designed to explode upon impact. In such instance, in view of the fact that the shell will have left the gun or other projecting implement and its case prior to explosion and will in fact depend upon impact to effect explosion, it will be unnecessary to include a fuse; the primary cap and detonating cap being disposed in line with the striking pin or operating member 8^a and engaged directly by the latter upon impact of the shell.

In the use of the retaining and releasing means for the striking member 8^a, it will probably be unnecessary to remove the locking pin 37^a for the movable member 35^a before discharging the shell since the force of impact will be quite sufficient to shear such locking pin when said movable member 35^a is moved inward upon impact. In such case, the movable member 35^a may be slotted or notched in line with the latches 28 so that the latter may be released, permitting movement of the striking pin 8^a under influence of the traction spring 12^a simultaneously with the displacement of a separating member for said latches.

In the arrangement shown in Fig. 4, the latches 28 are spread apart and held in the operative position by an interposed member 60 at the upper ends of the same which may be in the form of a ring washer 56, slotted at 57 so that the engaging ends of the latches may be definitely positioned with respect thereto. The movable member 35^a is held in the outer position by means of a spring

36^a, and is provided with a displacing projection 58 for engagement with the said ring washer 56 upon the shell striking; such impact immediately releasing the latches 28 from engagement with the striking member 8^a which is forced under the action of the spring 12^a into engagement with a primary cap 11^a mounted in a tubular stem 59 forming an anvil and centrally disposed with respect to the shell; a detonating cap 10^a being arranged directly below said primary cap.

In order that the latches may be free to swing inwardly and release the striking pin 8^a, the internal projection 58 of the member 35^a is preferably slotted in line with said latches, as indicated at 60; hence it will make no difference whether the said member 35^a is held in or forced outwardly by the spring 36^a after impact or not. In structures of this type, it will probably be desirable to give the member 35^a a cross section other than circular in order that it may be definitely guided for proper coaction of the latches with the slotted or apertured portion of such movable member.

The construction and arrangement of the several parts at the impact end of the shrapnel shell illustrated in Fig. 4, are, in other respects, substantially the same as those illustrated in Fig. 1.

In Fig. 6, I have shown another form of releasing means for the latches as applied to shrapnel, in which the internal projections of the member 35^b, indicated at 58^a, is carried in to an extent sufficient to provide a portion 61 to separate said latches; such member being held in the outward position by a spring 36^b. This member may have an enlarged cap or head such as illustrated in Fig. 3, as employed with a hand grenade, and a split cotter pin may be used to hold such member in the safety position. The projection 58^a is apertured at 62 so that when the latches are released by displacement of the portion 61 of said movable member 35^b, the ends of said latches will be free to enter said apertures when the striking pin 8^a moves them out of the way upon release thereby.

In Fig. 7, an arrangement substantially like that illustrated in Fig. 6 is provided, except that the movable member 35^c is provided additionally with a central stem or projection 63 designed to assist in displacing the striking pin as the latter is released from the latches; said pin 63 being moved into contact therewith upon impact.

In the structures shown in Figs. 4, 5, 6 and 7, the members 35^a, 35^b and 35^c, may be hexagonal, square, or of other polygonal shape so as to be properly positioned and maintain their position with respect to the latches in order that the latter may be released immediately upon said members being driven into the shell on impact. The screw

plugs 26 employed with the various structures, whether of the hand grenade type or otherwise, are preferably provided with hexagonal heads whereby they may be turned into position by the use of a wrench.

5 The internal shell 6 and various other parts of the internal mechanism may be made of aluminum, and preferably are made of such material, although the use of such 10 material is not essential to the operation of the structure.

15 In some instances it may be unnecessary to fill the explosive shell with any explosive material, high explosive or not, since I have found in practice that it is possible to shatter the shell with the use of detonating caps of a high explosive character.

20 In the shrapnel, the usual explosive material, shot and the like will be included; the same as well as the construction of such shrapnel forming no part of my invention.

25 While I have shown and described certain elements of my improved structure with more or less particularity, it will be understood that I do not wish to be limited to the precise construction or arrangements illustrated, and the claims are designed to cover the constructions shown as well as all mechanical equivalents of the same.

30 I claim:

1. The combination with an explosive member and a detonating cap mounted therein, of a carrier for said cap, a striking pin for engagement with said cap, said cap and pin being mounted in movable relation with respect to each other, a spring for effecting such movement of the movable part, latches for retaining the movable member in the inactive position, a slotted plate 35 carried by the explosive member in which said latches are mounted, means for holding the latches in their active position, and a plug member at the end of the shell having an outwardly projecting operative portion; 40 said plug member being movable inwardly to displace the latch retaining means and release the member supported thereby.

45 2. The combination with an explosive member and a detonating cap mounted therein, of a plunger carrying said cap, a relatively fixed striking pin for engagement with said cap, a spring for effecting such movement, latches for retaining the plunger in the inactive position, a slotted plate carried by the explosive member in which said latches are loosely mounted, means for holding the latches in their active position, and a plug member mounted at the end of the shell beyond the slotted plate and having an 50 outwardly projecting operative portion; said plug member being movable inwardly to displace the latch retaining means whereby the plunger supported by said latches may be released.

55 3. The combination with an explosive

member and a detonating cap mounted therein, of a plunger carrying said cap, a striking pin for engagement with said cap, a spring for imparting movement to said plunger, a screw plug carried at the end of said explosive member, a disk confined to the explosive member by said screw plug, latches for retaining said plunger in the inactive position loosely mounted in slots in said disk, means for holding said latches in plunger-retaining position, and a member disposed in the screw plug at the end of the shell and having an outwardly projecting portion; said member being movable inwardly to displace the latch retaining means whereby the movable plunger may be released to effect explosion of the detonating cap.

4. The combination with an explosive member having a detonating cap, of a plunger carrying said cap, a striking pin for engagement with said cap, a spring for imparting movement to said plunger to explode said cap against said striking pin latches for retaining said plunger in the inactive position, a disk carried at the end of the explosive member, said disk having alined slots radially disposed in which said latches are loosely mounted, means for holding said latches in the plunger-supporting 95 position comprising a member movable at the end of the shell and having an outwardly projecting portion and an inwardly projecting portion in engagement with said latches; inward movement of said member 100 displacing the latches and releasing said plunger to effect explosion of the detonating cap.

5. The combination, in a hand grenade, of a shell, an axially disposed tube extending longitudinally thereof, a plunger disposed in said tube, a detonating cap carried by said plunger, a striking pin against which said cap is carried by the plunger to effect explosion thereof, a spring for imparting movement to said plunger, a cupped member to position said tube, a slotted disk overlying said cupped member, means for securing said disk to the grenade, latches loosely mounted in said disk for retaining said plunger in the inactive position, means for holding said latches to retain the plunger comprising a member movable at the end of the shell, said member having an outwardly projecting portion for impact 115 and an inwardly projecting portion in engagement with said latches; inward movement of said member displacing the latches whereby the plunger may be released, and a spring for holding said member normally 120 outward.

6. The combination, in a hand grenade, of a cast metal shell having an explosive cap within the same, a movable plunger for carrying said cap, a tubular member in 130

which said plunger is movable, latches for supporting said carrier, a slotted disk confined in one end of the grenade in which said latches are loosely mounted, a spreader 5 for said latches, an impact member projecting from the end of the grenade and carrying such spreader, a spring for moving the plunger in its tubular member when released, a sheet metal wall closing the opposite 10 site end of the grenade, and a firing pin carried by said wall within the tubular member and in line with the cap-carrying plunger.

7. The combination, in a hand grenade, 15 of a screw plug closing one end of the same, a disk, a cup member, said disk and cup member being interposed between a shoulder on the shell of the grenade and said screw plug, a movable striking member within the 20 grenade, latches movably mounted in said disk for supporting said striking member, and a spreader for said latches.

8. The combination with an explosive shell, of an explosive cap, a carrier for the 25 same, a striking pin for said cap, one of said members being movable with respect to the other, latches supporting the movable member, a screw plug closing the impact end of said explosive shell, a disk, a cup member, 30 said disk and cup member being interposed between a shoulder on the shell of the explosive member and said screw plug, said disk being slotted and the latches being loosely mounted in said slots, a spreader 35 ring for holding said latches in the active position, a movable member mounted in said screw plug for displacing said ring to release the latches, and guiding means for said movable displacing device.

40 9. The combination with an explosive shell, of a fixed firing pin, a movable plunger in axial alignment with said firing pin, a tubular casing in which said plunger is mounted, primary and detonating caps carried by said plunger, a disk fixed in the end 45 of the shell, means loosely mounted in said disk for holding the plunger inactive, a spring for moving the plunger within the tubular casing when released, a releasing 50 member having a portion projecting from the end of the shell for impact and a portion projecting inwardly for maintaining said movable member inactive; inward movement of said releasing member permitting the 55 plunger to carry the explosive cap into contact with the fixed firing pin under the influence

of the spring, and means for holding said releasing member inactive.

10. The combination, in an explosive shell, of a hollow body, closures for the ends 60 of the same, a cupped member and a plate held in position by one of said closures, a movable plunger within the shell, latches movably mounted in said plate for supporting said plunger; the latter being arranged 65 to move through the cupped member, an outwardly projecting impact member carried by one of the end closures of the shell, a spring for holding said impact member in the projected position, a spreader for the 70 latches carried by said impact member, a detonating cap and a primary cap carried by said plunger, a firing pin carried by one of the end closures, and a spring for driving said plunger to move the primary cap into 75 engagement with the firing pin when the latches are released by inward movement of the impact member.

11. The combination, in an explosive shell, of a hollow body, detachable closures 80 for the ends of the same, a partition disposed at one end of said hollow body and held in position by one of said closures, a firing pin carried at the opposite end of said body, a tubular member confined between 85 said partition and the closure at the opposite end of the shell and inclosing said firing pin, a movable plunger within said tubular member, a spring for impelling the same, latches movably mounted in said plate for 90 supporting said plunger, a spreader for maintaining said latches in the active position, externally operable means for displacing said spreader to release said movable plunger, and a detonating cap and a primary cap carried by said plunger; the latter being movable into engagement with the 95 firing pin when the plunger is impelled by its spring.

12. In a hand grenade, the combination 100 with a shell having a detonating cap, a firing pin and means for actuating said firing pin, of a slotted plate confined to said shell, means for supporting said firing pin against the operation of its actuating means 105 including a plurality of latches loosely mounted in the slots of said plate, displaceable means for maintaining said latches in supporting position, and an externally operable member for actuating said displaceable 110 means.

HARRY E. ASBURY.
